UNITED STATES PATENT OFFICE.

HENRY MARTIN HOWELL, OF MONROE, LOUISIANA, ASSIGNOR, BY DIRECT AND MESNE ASSIGNMENTS, OF SEVEN AND ONE-HALF PER CENT. TO CHARLES SCHULTZE, SEVEN AND ONE-HALF PER CENT. TO RICHARD DOWNS, SEVEN AND ONE-HALF PER CENT. TO JOHN E. DOUGHTIE, SEVEN AND ONE-HALF PER CENT. TO SHELBY C. BLACKMON, SEVEN AND ONE-HALF PER CENT. TO ARTHUR KING, FIFTEEN PER CENT. TO LOUIS H. KRICKEL, AND THIRTY-FIVE PER CENT. TO SAMUEL KAPLAN, ALL OF MONROE, LOUISIANA.

DEMOUNTABLE RIM.

1,383,810.

Specification of Letters Patent.

Patented July 5, 1921.

Application filed January 6, 1920. Serial No. 349,723.

To all whom it may concern:

Be it known that I, HENRY MARTIN HOWELL, a citizen of the United States, and a resident of Monroe, in the parish of 5 Ouachita and State of Louisiana, have invented certain new and useful Improvements in Demountable Rims, of which the following is a specification.

My invention relates to demountable rims 10 and more particularly to an improved demountable rim of the type employing a removable outer tire-retaining flange.

An important object of the invention is 15 to provide an improvement of this character with fastening means for the outer removable tire-retaining flange in which the fastening action is equally and evenly distributed along the entire circumference thereof to provide the greatest strength, 20 durability and efficiency, and to prevent distortion of the various parts.

Other objects and advantages reside in 25 the certain novel features of the construction, arrangement and combination of parts which will become apparent as the description proceeds, reference being had to the accompanying drawings forming a part of 30 this specification and in which—

Figure 1 is a vertical sectional view showing 35 my invention embodied in a wire wheel construction, the plane of the section intersecting the locking flange;

Fig. 2 is a vertical sectional view showing 40 my invention embodied in a wooden wheel construction, the plane of the section lying between the locking flanges;

Fig. 3 is a fragmentary perspective view 45 illustrating one form of fastening means;

Fig. 4 is a fragmentary detail perspective 50 view illustrating the preferred construction of the ends of the enlarged head of the locking flange;

Fig. 5 is a side elevational view, the outer 55 tire-retaining flange being removed;

Fig. 6 is a fragmentary view in vertical 60 section of the form of my invention shown

in Fig. 1, the plane of the section lying between the locking flanges;

Fig. 7 is a fragmentary view in vertical section showing a modified form of fastening means; and

Fig. 8 is a fragmentary view in vertical section showing a still further modified form of fastening means.

Referring to the drawings, especially to 55 Figs. 2, 3, and 5, it will be seen that my invention is shown embodied in an automobile wheel of wooden construction including a hub 10, spokes 11, and felly 12. A felly band 12' is shrunk or otherwise secured upon 60 the felly 12.

Referring especially to Figs. 1, 6, 7, and 8, it will be seen that I have also shown my invention embodied in a wire wheel construction in which 13 represents the spokes 65 and 14 the wheel body which includes not only the fixed rim but the remainder of the wheel. This wheel body serves as both the felly and the felly band and consists merely of an annular ring in which the spokes are 70 countersunk. A depending integral plate 15 is also included in the wheel body.

In both embodiments of my invention the felly band is provided at its inner edge, that is, at the edge adjacent the vehicle, with a 75 vertical upstanding flange 15' and at its outer edge with a bevel 16 constituting an inclined surface. Both the flange 15' and the bevel 16 extend entirely around the circumference of the felly band. A removable 80 wedge ring 17 is positioned upon the felly band adjacent the upstanding flange 15' and presents an inclined surface 17', as shown.

The demountable rim consists of a base 85 section 18 having an inner integral tire-engaging and retaining flange 19 and having formed at its outer side an inner vertically depending locking plate 20, the inner face of which is adapted, when the rim is in position, to bear against the outer surface of the 90 felly. An outer tire-retaining and engaging flange 21 has integrally formed there-

with a vertically depending outer locking plate 22, the inner face of which is adapted, when the rim parts are assembled, to bear against the outer face of the inner locking plate 20. Both of the locking plates extend entirely around the circumference of the rim.

The demountable rim, when assembled, is adapted to be placed upon the wheel in proper position with respect thereto and properly spaced from the felly. For this purpose the under side of the base section of the rim is provided with an integral downwardly extending circumferential flange 23 having an inclined face 23' corresponding to the inclined face 17' of the wedge ring 17, and the under side of the base section is also provided at its outer side with a wedge ring 24 which may be removable if preferred, and which is formed with an inclined surface 24' corresponding to the inclined surface of the felly band. When in engagement these inclined surfaces co-operate to properly position the rim spaces from the felly band.

The locking plates 19 and 21 are provided with fastening means, which, when in locking position, prevent lateral movement of the tire retaining flange 20 with respect to the base section 15 of the rim and the inner tire-retaining flange 18, and common means is provided for preventing circumferential movement of the outer tire-retaining flange with respect to the other parts of the rim and for maintaining the demountable rim upon the wheel.

An important feature of my invention resides in the improved fastening means which consists, in general, and in all forms of the invention, of spaced arcuate locking flanges integral with the inner locking plate 20 and each having their outer ends provided with enlarged heads. In the form of my invention shown in Fig. 1, the arcuate flange is designated at 25^a and is of rectangular cross section and the enlarged head 26^a integral with the outer end of the flange 25^a is also of rectangular cross section and, moreover, is elongated in cross section with respect to the locking flange.

In the form of the invention shown in Fig. 7, the locking flange is designated at 25^b and the enlarged head thereof is designated at 26^b. Both the locking flange 25^b and its enlarged head 26^b have their top and bottom surfaces undercut, as shown in the drawing, and these surfaces are coincident and so blend into each other.

In the form of the invention shown in Fig. 8, the locking flange is designated at 25^c and the enlarged head, which is cylindrical, is designated at 26^c. The enlarged head 26^c presents a circular cross section, as shown in the drawing. The locking flange 25^c in this form is of a minute extent.

The locking plate 22 of the outer tire-retaining flange 21 is provided with a circumferential channel 27. Formed integral with the outer sides of the upper and lower walls of the channel 27 are arcuate shoulders 28 which are spaced circumferentially to permit entrance from the enlarged head 26 and the locking flange 25 in the channel 27 and are spaced radially to accommodate the locking flange when the plate 22 has been moved circumferentially with respect to the locking plate 20 so as to confine the enlarged head 26 in the channel 27 behind the arcuate shoulders 28 and thereby lock the tire-retaining flange 21 to the upper rim parts. As shown in Figs. 1, 7, and 8 the channel and the shoulders are formed to correspond with the form of the enlarged head 26.

Centrally of the open portions of the channel, that is centrally of the spaces between the shoulders of the channel, the locking plate 22 is provided with an opening 29, which, when the outer tire-retaining flange is in assembled position, is aligned with a like opening 30 provided in the locking plate 20. The locking flange and the co-operating locking arcuate shoulders, as well as the spaces therebetween and the openings 29 and 30, are preferably eight in number and the spaces and flanges are equal in circumferential extent to obtain the greatest possible locking action. When the outer tire-retaining flange is secured in place and its enlarged head is confined in the channel 27 by the arcuate shoulders 28, the openings 29 and 30 are aligned, as previously stated, and stud bolts 31 are inserted in these openings and secured in a nut 32 provided therefor in the felly. Suitable openings, of course, are provided for the stud bolts in the felly. As shown in Fig. 2 the stud bolts used with the wooden wheel construction are somewhat longer than the stud bolts used with the wire wheel construction in Fig. 6, in order to compensate for the difference in thickness of the felly 12 in the one instance and the plate 15 in the other.

To facilitate assembly of the outer removable tire-retaining flange, the enlarged heads 26 of the locking flanges are provided at each end on their inner side with beveled surfaces 26' as shown in detail in Fig. 4. These beveled surfaces engage the under side of the arcuate shoulders 28 and draw the locking plate 22 and the tire-retaining flange 21 inwardly toward the other rim parts.

A plurality of impact lugs 33 are provided on the outer tire-engaging flange 21 and are adapted to be operated upon by a hammer or the like to induce a proper circumferential movement of the rim flange 21 with respect to the other rim parts, in order to assemble and disassemble the rim.

A tire 24, indicated in dotted lines in Fig. 1, is mounted upon the base section of the rim and retained in position by the tire-retaining flanges 19 and 21.

5 In practice if it is desired to remove the tire 34 for purposes of replacing or repair, the stud bolts 31 are removed and the demountable rim may be bodily withdrawn from the wheel. The rim is then laid upon 10 the ground with the locking plates up and the impact lugs 33 are operated upon by a hammer or the like to induce circumferential movement of the locking plate 22 with respect to the other rim parts, until the arcuate shoulders 28 are withdrawn from behind the enlarged head 26 of the locking flange 25. The locking flange 25 and the enlarged head 26 then lie in the open portions of the channel and the arcuate shoulders 20 28 then lie in the open spaces between the locking flanges. The outer tire-retaining flange 21 may then be readily removed and the tire displaced for purposes of repair or replacement.

25 When it is desired to reassemble the rim, the tire is first placed upon the base section 18 and the outer retaining-flange 21 is then presented thereto so that the open portions of the channel 27 are opposite the locking flanges and their enlarged heads and the arcuate shoulders 28 are opposite the spaces between the flanges. The tire-retaining flange is then moved inwardly so that the locking flanges enter the open portions of 30 the channel 27 and the arcuate shoulders 28 lie in the open spaces between the flanges. The locking plate 22 is then moved circumferentially with respect to the locking plate 20, the inclined surfaces 26' of the enlarged 35 heads of the locking flanges engage behind the arcuate shoulders 28 and force the locking flanges behind the arcuate shoulders thereby locking the outer retaining flange in the other rim parts. When the proper 40 circumferential movement has been completed, the stud bolts 31 are then inserted in the openings 29 and 30 and threaded home in the nut 32 to secure the rim upon the wheel. The locking action is operative to 45 approximately one-half the circumference of the wheel. This is the greatest extent of locking action possible, and being evenly and equally distributed provides the greatest strength, durability, and efficiency, and 50 prevents distortion and corresponding inefficiency of the various rim parts.

I claim:

1. A demountable rim of the character described comprising the combination with a 60 rim base section, an inner tire-retaining flange integral with said base section and a removable outer retaining flange, of an inner locking plate integral with said base section, spaced arcuate locking flanges integral with said inner locking plate, each of

said flanges having an enlarged head spaced from the inner locking plate, an outer locking plate integral with said removable outer tire-retaining flange having a circumferential channel on its inner side and provided with a plurality of arcuate shoulders spaced circumferentially to permit entrance of the enlarged head in the said channel and spaced radially to accommodate said arcuate flanges when said enlarged heads are confined behind said shoulders, and means for maintaining said locking plates against circumferential movement, all as and for the purposes set forth.

2. A demountable rim of the character described comprising the combination with a rim base section, an inner tire-retaining flange integral with said base section and a removable outer retaining flange, of an inner locking plate integral with said base section, spaced arcuate locking flanges integral with said inner locking plate, each of said flanges having an enlarged head spaced from the inner locking plate, and an outer locking plate integral with said removable outer tire-retaining flange having a circumferential channel on its inner side and provided with a plurality of arcuate shoulders spaced circumferentially to permit entrance of the enlarged head in the said channel and spaced radially to accommodate said arcuate flanges when said enlarged heads are confined behind said shoulders.

3. A demountable rim of the character described comprising the combination with a rim base section, an inner tire-retaining flange integral with said base section and a removable outer retaining flange, of an inner locking plate integral with said base section, spaced arcuate locking flanges integral with said inner locking plate, each of said flanges having an enlarged head spaced from the inner locking plate, the under side of the enlarged head at each end of the locking plate being beveled to provide an inclined surface, and an outer locking plate integral with said removable outer tire-retaining flange having a circumferential channel on its inner side and provided with a plurality of arcuate shoulders spaced circumferentially to permit entrance of the enlarged head in the said channel and spaced radially to accommodate said arcuate flanges when said enlarged heads are confined behind said shoulders.

4. A demountable rim of the character described comprising the combination with a rim base section, an inner tire-retaining flange integral with said base section and a removable outer tire-retaining flange, of an inner locking plate integral with said base section, spaced arcuate locking flanges integral with said inner locking plate, each of said flanges having enlarged cylindrical heads, arcuate cylindrical heads spaced from

the inner locking plate, an outer locking plate integral with said outer removable tire-retaining flange having a circumferential channel on its inner side cylindrical in 5 cross section and open to the inner under side of the outer locking plate, and provided with a plurality of arcuate shoulders spaced circumferentially to permit entrance of the enlarged head into said channel and spaced radially to accommodate said arcuate flange when said enlarged heads are 10 behind said shoulders.

HENRY MARTIN HOWELL,
